US00D990957S

(12) **United States Design Patent** (10) **Patent No.:** **US D990,957 S**
(45) **Date of Patent:** **** Jul. 4, 2023**

(54) **BEVERAGE BREWING APPARATUS**

(71) Applicant: **Starbucks Corporation**, Seattle, WA (US)

(72) Inventors: **David H. Wykes**, Seattle, WA (US); **Ryan M. Gorham**, Kirkland, WA (US); **Kay H. Kim**, Seattle, WA (US); **Joseph E. Gormley**, Mercer Island, WA (US)

(73) Assignee: **Starbucks Corporation**, Seattle, WA (US)

(**) Term: **15 Years**

(21) Appl. No.: **29/790,291**

(22) Filed: **Nov. 17, 2021**

(51) LOC (14) Cl. **07-01**

(52) U.S. Cl. **D7/307**

(57) **CLAIM**

The ornamental design for a beverage brewing apparatus, as shown and described herein.

DESCRIPTION

FIG. 1 is a top perspective view of a beverage brewing apparatus showing a first embodiment our design; FIG. 2 is a bottom perspective view thereof;

FIG. 3 is a front elevation view thereof;

FIG. 4 is a rear elevation view thereof;

FIG. 5 is a right-side elevation view thereof;

FIG. 6 is a left-side elevation view thereof;

FIG. 7 is a top plan view thereof; and

FIG. 8 is a bottom plan view thereof;

FIG. 9 is a perspective view of a beverage brewing apparatus showing a second embodiment of our design; FIG. 10 is a bottom perspective view thereof;

FIG. 11 is a front elevation view thereof;

FIG. 12 is a rear elevation view thereof;

FIG. 13 is a right-side elevation view thereof;

FIG. 14 is a left-side elevation view thereof;

FIG. 15 is a top plan view thereof; and,

FIG. 16 is a bottom plan view thereof.

The broken lines shown in the drawings represent portions of the beverage brewing apparatus that form no part of the claimed design.
